UNITED STATES PATENT OFFICE.

CANCEL THOMAS DOCTER, OF VANWINKLE, GEORGIA.

GRAIN-DOOR ATTACHMENT.

SPECIFICATION forming part of Letters Patent No. 705,655, dated July 29, 1902.

Application filed April 27, 1901. Serial No. 57,770. (No model.)

To all whom it may concern:

Be it known that I, CANCEL THOMAS DOCTER, a citizen of the United States, residing at Vanwinkle, in the county of Fulton and State 5 of Georgia, have invented a new and useful Grain-Door Attachment, of which the following is a specification.

This invention relates generally to grain-car-door attachments, and more particularly 10 to the means for attaching the door to the car.

The object of the invention is to provide simple and efficient means for fastening the door when in use and also for securing it when not in use; and with these objects in view 15 the invention consists, essentially, in providing the door with a detachable hinge member adapted to be connected to one end of the door for the purpose of engaging a perforated plate secured to one of the door-posts and in 20 providing a slideable connection between the opposite end of the door and a rod fixed upon the interior of the car whereby the door can be elevated and suspended from the top of the car when not in use.

25 The invention consists also in certain details of construction and novelties of combination, all of which will be fully described hereinafter and pointed out in the claims.

In the drawings forming a part of this specification, Figure 1 is a view showing the practical application of my invention, the view being taken from the exterior of the car and showing the door in use. Fig. 2 is a sectional perspective view taken from the interior and 35 showing the position the door occupies when not in use. Fig. 3 is a horizontal sectional view taken on the line 3-3 of Fig. 1. Fig. 4 is an interior detail view showing the free end of a car-door, and Fig. 5 is an end view of 40 the door.

My invention is applicable to all constructions of cars, and when applying my door to the car I arrange an angle-plate A upon the left-hand post of a door-frame provided with 45 perforations A', and a rod B is attached to the right-hand door-post upon the inner face, as most clearly shown in Figs. 2 and 4. The door C is made somewhat longer than the width of the doorway, as most clearly indicated in Fig. 3, and at its left-hand end is

bound by a strip of iron D. A forked hinge-like locking member E is adapted to be secured to the left-hand end of the door upon the exterior, the hooked ends E' engaging the openings A' produced in the angle-plate A. 55 The central or end portion E² of the locking member is slotted to pass over an eyebolt F, arranged upon the exterior of the door, and a pin G, carried by the chain H, securely fastens the end E² upon the staple or eyebolt 60 F. The forks of the locking member pass over and rest upon the guide-eyes I, and through which a bolt K passes, said bolt serving to hold the forks of the member in their proper position when in engagement with the 65 angle-plate.

As before stated, the door is somewhat longer than the width of the doorway, and when the door is closed its free end rests upon the inner face of the right-hand door-post, as 70 most clearly illustrated in Figs. 2 and 4.

A clip L is arranged upon the right-hand end of the door, and a chain M is attached to this clip and carries a ring N, which slides upon the rod B, thus connecting the door to 75 the said rod. When the door is in use, the various parts are arranged as shown in Fig. 1. When it is desired to remove the door, the locking-bolts are withdrawn and the locking member E swung outwardly until its hooked 80 ends disengage the perforated angle-plate. The door can then be elevated, as shown in Fig. 2, and suspended from the top of the car by means of hooks O, the sliding connection between the right-hand end of the car 85 and the rod B permitting such elevation and suspension.

It will thus be seen that I provide an exceedingly cheap, simple, and efficient means for attaching a car-door to the car. 90

Having thus fully described my invention, what I claim as new, and desire to secure by Letters Patent of the United States, is—

1. In a device of the kind described, the combination with the door, of a perforated 95 angle-plate, the forked hinge-like locking member having hooked ends to engage the perforations in the angle-plate, and means for attaching said locking member to the door, substantially as described. 100

2. The combination with the door, of the perforated angle-plate, the forked hinge-like locking member having hooked ends, the opposite end of said locking member being slotted, the eyebolt or staple over which the slotted end fits, the guide-eyes upon which the forks of the locking member rest, and the

locking-pins passing through the eyes and connecting the door and member, substantially as described.

CANCEL THOMAS DOCTER.
